KENTUCKY.

SMOKE-CONSUMING APPARATUS FOR LOCOMOTIVE AND OTHER BOILERS.

1,159,085.

Specification of Letters Patent.

Patented Nov. 2, 1915.

Application filed November 24, 1914. Serial No. 873,819.

To all whom it may concern:

Be it known that we, JOHN E. PRICE, WILLIAM R. PRICE, and CHARLES L. HILDRETH, citizens of the United States, and residents of Covington, in the county of Kenton and State of Kentucky, have invented a certain new and useful Improvement in Smoke-Consuming Apparatus for Locomotive and other Boilers, of which the following is a specification.

This invention relates to smoke-consuming devices that are used more especially in the outlet funnels or stacks of steam-boilers, and its object is to provide a device concentrically within the smoke-stack of a locomotive-engine or the like, above the draft-line, that will somewhat suspend or hold, in abeyance, the smoke in its passage therethrough by means of a combined or intermingled steam and air blast whereby the particles of carbon liberated from the fire-box or furnace are given the desired supply of oxygen and consumed or destroyed and not permitted to escape from the mouth or exit end of the stack into the surrounding atmosphere, and without detriment to the required draft in the stack but, on the other hand, to somewhat improve it at no material sacrifice of economy.

The features of the invention will be fully hereinafter described and then particularly defined in the claim that follows.

In the accompanying sheet of drawings, Figure 1 is a plan view of our device showing it in position in a fragmentary portion of the fore end of a locomotive-engine; Fig. 2, an elevation of the same but with part of the stack broken open and in section to more clearly show the internal steam-ring and distributing air and steam nozzle structure; and Fig. 3, a detail sectional view taken on the line *a*, *a*, of Fig. 1 and showing a fragment of the said internal steam-ring and one of the exit steam nozzles or spray devices thereof.

1 indicates the fore end of a locomotive-boiler having the customary stack-saddle 2 and the upright stack or funnel 3 the latter being of any suitable height and diameter and above the draft-line, as customary.

4 is a horizontal, hollow ring suitably supported within the stack at the end of a steam supply-pipe 5 that leads to a steam-source-control in the cab of the engine. This ring has a series of perforated nozzles or

spray devices 6 carried by radial upwardly-disposed tubes 7 that project inwardly therefrom, as best seen in Fig. 3. In Fig. 1 we have shown six of these spray-nozzles, but it is obvious that a greater or less number may be employed to suit conditions. These steam spray nozzles or diffusers may also be of other than the spherical form.

8 indicates each one of a pair of air-receptacles, each one carrying at its opposite ends a jet-tube 9 that extends through the wall or shell of the stack into its interior directly beneath the said steam-ring 4, as seen in Figs. 1 and 2. These jet-tubes each carry a perforated head or nozzle 10 that diffuses the air from the receptacles 8 that, in turn, get their supply under pressure through the pipes 11 that lead to the air-collecting devices on the engine-cab where they are held under due control.

The air-supply pipes 11 are each furnished with exit nozzles or jets 12 (shown in dotted-lines in Fig. 2) that are mounted in the lower pendent ends 13 of the air-receptacles 8 (Fig. 2) and are of smaller diameter than the bore of the said ends 13 so as to provide for an air-inlet from the surrounding atmosphere to augment the flow of air and oxygen to the exit-nozzles 10 that are preferably located on the same horizontal plane as that of the steam-nozzles 6 and lie adjacent the latter, as best seen in Fig. 1. In operation, the air issuing from the nozzles 10 mingles with the dry steam passing under duly controlled pressure from the nozzles 6 and is duly heated thereby, which, together with the flame or high degree of heat that passes through the boiler flues or tubes from the fire-box, is sufficient to consume or burn the particles of carbon or soot that are ordinarily liberated from the furnace in the operation of the locomotive or other steam boiler in connection with which our device is applicable.

The device is preferably but not essentially arranged at the middle of the stack, but it can be placed at any point above the draft-line that lies below the saddle 2.

We claim:—

In a smoke-consuming apparatus for locomotive and other steam boilers, the combination of an exit stack or funnel, a horizontal, circular, steam-chamber or hollow steam-ring having a plurality of radial, upwardly-disposed steam spray-nozzles and mounted

110

concentrically within said stack on a plane above the draft-line of the boiler, a steam supply-pipe leading to said hollow ring or chamber from a controlled-source, a pair of 5 horizontal semi-circular air-receptacles mounted opposite each other outside the stack with the latter intervening and having at their opposite ends, radial, upwardly-disposed spray-nozzles that extend through 10 punctures made in the cylindrical shell of the stack above said draft-line and are

adapted to discharge outside or external air under pressure adjacent said radial steam spray-nozzles, and air pumping conductors leading to said pair of semi-circular air-receptacles from a controlled source. 15

JOHN E. PRICE.
